PROTECTOR MECHANISM FOR LOOMS

William A. Blanchard, Millbury, Mass., assignor
to Crompton & Knowles Loom Works, Worcester, Mass., a corporation of Massachusetts

Application December 4, 1948, Serial No. 63,580

5 Claims. (Cl. 139—345)

1

This invention relates to improvements in protector mechanisms for looms and it is the general object of the invention to provide such a mechanism with an improved form of dagger which can be held securely to the protector rod in adjusted angular position.

Fly shuttle looms ordinarily have some form of protector mechanism to effect loom stoppage should the shuttle fail to box at the proper time in the loom cycle. Many of these mechanisms employ a rod extending along the lay and having fingers at the ends thereof for engagement with the shuttle box binders and having also daggers for engagement with stopping mechanism. In wide looms there may be several daggers on the rod and it is desirable to be able to set these daggers in alignment with each other for cooperation with their respective stopping mechanisms distributed along the breast beam of the loom. While the invention to be set forth hereinafter is more particularly adaptable to wide looms such as those used for the weaving of paper makers felts, the invention is equally applicable to narrower looms with only two daggers.

In order that the daggers may be firmly secured to the protector rod but also be angularly adjustable thereon it is an important object of the present invention to provide each dagger with protector rod clamping sleeves or the like through which a clamping bolt passes. The latter when tightened forces the sleeves against the rod to hold the dagger against angular movement relative to the rod.

With these and other objects in view which will appear as the description proceeds, the invention resides in the combination and arrangement of parts hereinafter described and set forth.

In the accompanying drawings, wherein the invention is shown as applied more particularly to a wide loom,

Fig. 1 is a vertical section through part of a loom having the invention applied thereto,

Fig. 2 is an enlarged detailed plan view of the protector rod looking in the direction of arrow 2, Fig. 1, showing four daggers,

Fig. 3 is a vertical section on line 3—3, Fig. 2, the stopping mechanism being shown in dot and dash lines,

Fig. 4 is an enlarged horizontal section on line 4—4, Fig. 3,

Fig. 5 is a bracketed view showing front and side elevations at the left and right respectively of the upper clamping member, and

Fig. 6 is a view similar to Fig. 5 but showing the lower clamping member.

2

Referring particularly to Fig. 1, the loom frame 10 supports a lay 11 which rocks backwardly and forwardly in the lay around a rocker shaft 12. Each end of the lay is provided with a shuttle box one of which is designated at 13. Each shuttle box has a box front in the form of a binder 14 which is pushed forwardly, or to the left as viewed in Fig. 1, by the shuttle S when the latter enters the shuttle box.

10 The loom includes a breast beam 15 on the under side of which is mounted a conventional stopping mechanism such as a bunter lever 16. A protector rod 17 extends lengthwise of the lay 11 and is mounted for rocking with respect to the latter in bearings one of which is indicated at 18, Fig. 1. Extending upwardly from each end of the protector rod is a protector finger 19 for engagement with the associated shuttle binder. In Fig. 1 one of these fingers is shown, but it is to be understood that there will be a similar finger at the opposite end of the loom. Also secured to the protector rod are protectordaggers designated generally at D for cooperation with the bunter levers 16. There will be a bunter for each dagger, and in wide looms there will be several daggers distributed along the length of the protector rod.

15 During loom operation the shuttle S is picked back and forth across the lay and the latter reciprocates in a more or less horizontal direction. As the lay is approximately between front and back center positions, or at top center, and moving to the right as viewed in Fig. 1, the shuttle will be picked through the warp shed designated at W. At a later time in the loom cycle the shuttle if running properly will enter one of the shuttle boxes as the lay is moving forwardly and move the corresponding shuttle binder 14 forwardly against a protector finger and cause rocking of the protector rod 17 in a counter-clockwise direction as viewed in Fig. 1, thereby lowering the daggers D to a position where they will miss their corresponding bunters 16 to permit continued running of the loom. If, on the other hand, the shuttle is tardy in arriving at its shuttle box the protector rod will not be rocked but will be held in position to cause engagement of the bunters 16 by the daggers D to effect loom stoppage as the lay advances. This stoppage will prevent the shuttle if trapped in the shed from breaking the warp threads.

20 Any of the usual means may be employed for holding the protector rod yieldingly in position with its daggers aligned with their bunter levers 16, such means not being shown herein but ordinarily comprising a coil spring wrapped around the rod 17 and having one end operatively en-

gaged with the latter and having the other end connected to the lay.

The matter thus far described, except for the details of the dagger D as will be set forth herein-after, may be of usual construction and operate in the ordinary manner.

As shown more particularly in Fig. 2 the protector rod 17 is provided with four daggers D, but since all of these daggers are alike a detailed description will be given of but one of them, namely, the one at the right end of Fig. 2.

The dagger D comprises a body 25 having a pointed forward end 26 for engagement with the bunter lever 16. The rear end of the body 25 is enlarged in a vertical direction as at 27 and has a horizontal bore 28 which snugly fits the protector rod 17. A second bore 29 extending vertically through the enlarged part 27 is preferably at right angles to the bore 28 and communicates with the latter but is located largely at the right thereof as shown in Fig. 3.

Fitting snugly in the bore 29 are upper and lower tubular clamping members or sleeves 30 and 31, respectively, which may both be alike. The bolt 32 extends through the tubular clamping members 30 and 31 and has a head 33 which engages the under side 34 of the bottom clamp 31. The latter preferably extends a slight distance below the bottom 35 of part 27 of the dagger body. A clamping nut 36 is screw threaded on the upper end of the bolt 32 and a lock washer 37 preferably of a diameter not exceeding the outside diameter of the upper member 30 may be located between the latter and the nut.

The upper clamp member 30 has the lower part of one side thereof formed with an arcuate wedging surface 40 cut preferably on the same radius as that of the protector rod, and the upper part of the lower clamp member is provided with a wedging arcuate surface 41 similar to surface 40.

In assembling, the rod 17 will be fitted into bore 28 and the body 25 slipped along the rod to its correct position. With rod 17 extending partly into bore 29 the upper and lower tubular clamping members will then be inserted into the bore 29 with the wedging surfaces 40 and 41 facing adjacent parts of the curved or cylindrical surface of the protector rod 17. The bolt 32 is then passed through the two wedging members and the nut 36 tightened to clamp the wedging surfaces 40 and 41 firmly against their corresponding parts of the protector rod. If it be desired to change the angular position of the dagger relatively to the protector rod the nut 36 can be slackened and after the adjustment is made retightened to clamp the members 40 and 41 tightly against the protector rod in the newly adjusted position.

The tubular clamping members have a snug fit with the bore 29 and the rod 17 will have a similar fit with the bore 28. By tightening the clamping members relatively large areas of the latter and the rod 17 will be forced into tight holding relation to adjacent surfaces of the dagger body. Both of the upper and lower clamping members 30 and 31 are shown herein as being of the same length so that they are in effect duplicates of each other, but this is not a necessary relation. It will also be seen from Fig. 3 that considerably more than one-half of the periphery of the rod 17 is in engagement with the bore 28 in order to hold the dagger in proper position on rod 17 before the clamping members and bolt are placed in position.

From the foregoing it will be seen that the

invention sets forth an improved form of protector mechanism employing a protector rod having mounted thereon a protector dagger which includes a pair of tubular clamping members forced against the rod by a bolt passing through the members. By loosening the nut 36 the angular position of the dagger can be changed with respect to the protector rod. Furthermore, by having the lower end of the bottom clamp project normally below the bottom 35 assurance is given that both clamping members can be forced tightly against the protector rod.

Having thus described the invention it will be seen that changes and modifications of the foregoing specific disclosure may be made without departing from the spirit and scope of the invention.

What is claimed as new is:

1. In protector mechanism for a loom, a protector rod, a protector dagger through which the rod passes, a pair of tubular clamping members 20 slidable in the dagger along an axis extending transversely of the rod, one member having a wedging surface engaging one part of the rod and the other member having another wedging surface 25 engaging another part of the rod, and means 30 passing through said members drawing the latter together by movement along said axis to effect tight engagement of said wedging surfaces against the parts of the protector rod corresponding thereto.

2. In protector mechanism for a loom, a dagger having a bore extending horizontally therethrough, a protector rod in said bore, said dagger having a second bore extending vertically therethrough and communicating with the first bore and into which part of the protector rod extends, a pair of tubular clamp members in the second bore, one above and the other below the rod, and means 40 passing through said members drawing the latter toward each other in said second bore and into tight holding relation with said rod and dagger.

3. In protector mechanism for a loom, a dagger having a bore extending horizontally therethrough and having a second bore extending vertically therethrough and communicating with the first bore, a protector rod in the first bore extending partly into the second bore, a pair of tubular clamp members in the second bore, one above the rod and having a wedging surface for engagement with one part of the rod and the other member below the rod and having a wedging surface for engaging another part of the rod, and means drawing said members toward each other in said second bore forcing said wedging surfaces against the corresponding parts of the rod to establish firm holding relation between the rod, members and dagger.

4. In protector mechanism for a loom, a dagger having a bore extending horizontally therethrough, a cylindrical protector rod in said bore, said dagger having a second bore extending vertically therethrough and communicating with the first bore, part of the protector rod extending into the second bore, a pair of tubular clamp members within and closely fitting the second bore but movable therein toward each other, one member being above the rod and having a wedging surface engaging one part of that part of the rod extending into the second bore and the other member being below the rod and having a wedging surface engaging another part of that part of the rod extending into the second bore, and means 75 drawing said members toward each other in said

second bore forcing said wedging surfaces against the corresponding parts of the rod to establish firm holding relation between the rod, members and dagger.

5. A dagger for a loom protector rod, said dagger having a bore therethrough to receive the protector rod and having another bore therethrough communicating with the first bore and extending transversely of the latter, a pair of tubular clamping members in the second bore, and a bolt extending through said members by

which the latter may be drawn toward each other in said second bore.
